(57) **CLAIM**

The ornamental design for a product container, as shown and described.

DESCRIPTION

FIG. 1 is a top and front perspective view of a product container showing my new design;

FIG. 2 is a front elevational view thereof, the sides adjacent and rear being identical in appearance;

FIG. 3 is a top plan view thereof;

FIG. 4 is a bottom plan view thereof;

FIG. 5 is an exploded top and front perspective view thereof;

FIG. 6 is a top plan view thereof, with the cap removed;

FIG. 7 is an exploded top and front perspective view thereof, with the broken-line disclosure of a product roll being for illustrative purposes only and forming no part of the claimed design;

FIG. 8 is a top and front perspective view of the interior component thereof;

FIG. 9 is a front elevational view of the interior component thereof, the sides adjacent and rear being identical in appearance;

FIG. 10 is top plan view of the interior component thereof; and,

FIG. 11 is a bottom plan view of the interior component thereof.
